UNITED STATES PATENT OFFICE

BASILIO POLCARI, OF SOMERVILLE, MASSACHUSETTS

SANITARY DOORKNOB

Application filed November 11, 1929. Serial No. 406,466.

My invention relates to sanitary devices, and more particularly to sanitary door knobs.

The human hand is open to attack by a number of diseases, and some of these diseases are contagious, so that persons having any of them taking hold of a door knob may leave dangerous germs thereon, where the next person who comes and takes hold of the knob may become infected with disease. The hands more than any other part of the body are liable to come into contact with other persons and things. For instance it is easy for the hands to become infected with poison oak, erysipelas, itch, leprosy, etc. When persons having contagious diseases in their hands take hold of door knobs, the disease germs are left there in position to be taken up by the hand of the next person who comes and takes hold of the knob. And thus disease is spread. The person who brings the germs may have a sound hand, with the skin unbroken anywhere, so that he will be unconscious of having been the carrier of dangerous germs; but the next person who comes and takes hold of the knob may be a person who is specially liable to infection by the kind of germs left on that door knob by the previous caller. It has often happened that contagious diseases have been mysteriously spread, doubtless by persons who did not know that they themselves were the real carriers and distributors of the diseases.

The present invention proposes to prevent the spread of contagious diseases through the medium of contaminated door knobs.

My object is to provide a door knob constructed to carry a disinfectant inside of it, and so arranged that the disinfectant can gradually pass out through the knob to the outer surface thereof distributing itself over said surface, and especially those parts of the surface which most commonly come in contact with the hand that pulls or turns the knob.

A further object is to so construct the device that water filtering through the perforations therein during a storm will not be permitted to come into contact with the disinfectant carried within the knob.

Other objects will appear in the subjoined description.

A leading feature of the invention consists of a hollow door-knob carrying a disinfectant inside of it, and having perforations distributed over its shell for the escape of minute portions of the disinfectant from the inside surface of the knob to the outside surface thereof.

Another important feature consists of an arrangement inside the knob for holding a portion, at least, of the disinfectant central of the knob and protected from possible contact with water filtering into the knob through its perforations, during times of storm.

The invention consists in certain novel features of construction and arrangement of parts, as will be hereinafter described and claimed, reference being had to the accompanying drawings, in which Fig. 1 is a top plan view of my improved door knob. Fig 2 is a bottom plan view thereof. Fig. 3 is an elevational view of the outer end of the knob; and Fig. 4 is a horizontal section through the knob.

The knob may be made of any desired material, but brass is usually employed. It has the usual hollow portion 1, provided with the integral shank or neck 2. The main portion 1 of the knob is provided with a plurality of small bores or openings 3^a, 3^b, 3^c, and 3^d, distributed over it in any desired or preferred manner, as will be more fully pointed out hereafter.

The collar 2 of the knob is provided with the usual square opening 4 for the reception of the square bolt 5 which passes through the same, and is secured therein in the usual manner by the screw 6.

The square bolt 3 differs from the ordinary bolt in one respect, namely; that its inner end extends inwardly through the main body portion of the knob nearly, but not quite, to the end-wall of the knob; and this inwardly projecting portion 5^a of the square bolt 5 has a central bore 7 extending inwardly from the end thereof for a purpose presently to be explained.

The broad principle in view at this point

is to introduce a disinfectant into the knob through the collar-opening 4, which disinfectant will gradually work out through the perforations 3, and become diffused over the outer surface of the knob, and also spread on that surface by the hand of the operator.

This disinfectant is made preferably in the form of round balls or pills 8 as indicated in Fig. 4 of the drawings. These balls or pills roll and tumble around inside the knob as it is rotated, so that the disinfectant is applied to the inner surface of the knob, and passes out through the perforations 3, and spreads from them over the outer surface. The outer ends of these openings are flared as shown in Figs. 1, 2, and 3, of the drawings, in order to increase the area of the ends of the openings coming into contact with the hands that take hold of the knob, and also to impart to the disinfectant a lateral turn as it escapes from the perforations.

These perforations may be distributed over the knob in my desired manner. In the drawings, I have shown the upper side of the knob provided with three perforations indicated by 3^a and 3^b (see Fig. 1), and the under side provided with the openings 3^c and 3^d (see Fig. 2).

When a person takes hold of the knob, the end of the thumb will naturally cover the perforation 3^a, while the ball of the thumb will cover the openings 3^b. The forefinger coming under the knob will naturally cover the perforations 3^c, and the second or middle finger will cover the perforations 3^d. The thumb and fingers in grasping the knob in this way will get some of the disinfectant on them, and they will spread it over the outer surface of the knob all around the perforations and between them. And again when the knob is brightened up by the house-keeper, the disinfectant coming out through the perforations will be caught and applied all over the outer surface of the knob as it is being polished.

The balls or pills of the disinfectant are also placed in the end bore 7 of the square bolt 5, as shown in Fig. 4 of the drawings. This arrangement is specially desirable when the knob is placed on the windward side of a house where the rains and storms beat upon it, causing water to percolate through the perforations to the inside of the knob where it might unduly act upon and dissolve the balls of disinfectant. It will be seen that however much the rain may percolate through the knob it cannot touch the balls in the bore 7, but since the inner end of the square bolt 5 is slightly spaced from the wall of the knob, as indicated at 9 in Fig. 4, sufficient air will reach the balls within the bore 7 to gradually volatilize the balls, thus permitting their substance to im-

perceptibly pass out first through the narrow space 9, and afterwards through the perforations 3^a, 3^b etc.

The disinfecting balls shown in Fig. 4 outside the bore 7 may be omitted and only those shown in the bore 7 employed, or vice versa, as the need of the case in hand, or the preference of the user, may dictate.

From the foregoing, the operation of my device is fully apparent. It only remains to be said that when the disinfectant balls inside the knob have become exhausted, it is only necessary to unscrew the screw 6 and withdraw the square bolt 5, in order to recharge the device, as at first.

Having now described the principles of my invention and shown one practical embodiment thereof, I yet do not wish to be confined to the exact showing made, but desire protection on all that comes clearly within the spirit and scope of my invention.

What I claim as new and desire to protect by Letters Patent is:

1. A hollow door knob having openings leading from the outer surface of the knob to the interior thereof; a knob bolt extending into the knob through the neck thereof and projecting from the neck inwardly into the main body of the knob, said inwardly projecting portion of the bolt having a longitudinal recess extending inwardly from the end thereof; and a disinfectant in lump form carried in said recess, the opening in the end of the bolt leading into said recess being partially closed to prevent the escape of the disinfectant in bulk from said opening in the bolt, but left sufficiently open to permit the access of air thereto, whereby to volatilize the disinfectant and cause its gradual escape from the knob through the openings therein.

2. A hollow door knob having openings leading from the outer surface of the knob to the interior thereof; a knob bolt extending into the knob through the neck thereof and projecting from the neck inwardly into the main body of the knob and terminating at a point slightly spaced from the end wall of the knob, said inwardly-projecting portion of the bolt having a longitudinal opening leading inwardly from the end thereof; and a disinfectant carried in said opening; whereby the disinfectant may be attacked by the air entering at the end of said opening, but will be held against escape in bulk therefrom by the near proximity of the inner end of the bolt to the end wall of the knob.

In testimony whereof I affix my signature.

BASILIO POLCARI.
